UNITED STATES PATENT OFFICE.

WARREN A. SIMONDS, OF BOSTON, AND SETH WARNER, OF EAST HAMPTON, ASSIGNORS TO SETH WARNER, OLIVER WARNER, OF NORTHAMPTON, AND ALBERT L. FERNALD, OF BOSTON, MASSACHUSETTS.

IMPROVEMENT IN TREATING GAS FOR ILLUMINATION.

Specification forming part of Letters Patent No. 38,017, dated March 24, 1863.

To all whom it may concern:

Be it known that we, WARREN A. SIMONDS, of Boston, in the county of Suffolk and State of Massachusetts, and SETH WARNER, of East Hampton, in the county of Hampshire and State aforesaid, have invented a new and improved method for carbonizing the natural atmosphere of all seasons without regard to temperature; and we do hereby declare that the following is a full and exact description thereof, reference being had to the accompanying drawings, and to the letters and figures of reference marked thereon.

The nature of our invention consists in carbonizing the atmosphere by forcing it through light and volatile liquids—like naphtha, alcohol, or ether—and purifying the same for purposes of illumination, in substitute for all kinds of gas which are manufactured by destructive distillations.

To enable others skilled in the art to make and use our invention, we will proceed to describe its construction and operation.

Figure 1 is a perspective view of our apparatus as may be used for carbonizing the air for illuminating purposes. Fig. 2 is an interior and sectional view of the vessel or box used for the carbonization of the air. Fig. 3 is an interior or sectional view of our purifying vessel or box.

A and B represent a gasometer or tank and holder, with a frame or fixture connected to guide the holder as it may rise or fall, to be constructed in the same manner, with supply and discharge pipes, as those now in use in ordinary gas-works; but instead of filling the holder B with gas we fill it with air, by means of a force-pump or other mechanical arrangement.

In Fig. 2, letter C represents the carbonizing box or vessel, which is divided into four compartments by three partitions at equal distances, and made tight at the top and sides, and to extend to within about two inches of the bottom. In each compartment there is an inlet-pipe, a, which enters through the top and about the center of said compartments, and extends to within about three inches of the bottom. The outlet-pipes b b b are near the top of the vessel. Three of the outlet-pipes b b

are connected with the dip or inlet pipes a a a, and extend through and over, in half-circular form, from one compartment to another. The said compartments F F F F are packed or stuffed with curled hair, or other material to answer the same purpose, for the purpose of bringing the air more thoroughly in contact with the liquids in the compartments, and thereby facilitating carbonization. The carbonizing box or vessel is to be filled about four and a half inches from the bottom or two inches from the lower end of the dip-pipes a a a with naphtha and alcohol, or any light and volatile inflammable liquids.

E is a round or globular reservoir through which to fill the carbonizer C.

J is an inlet or screw cap through which to fill the reservoir E. The pipe g, connected to top of C, from thence to top of E, with a cock, No. 7, attached, will equalize the pressure when cock No. 7 is opened, so that the liquid in E will flow into C through the pipe h when cock No. 6 is opened. When it becomes necessary to fill E, the cocks 6 and 7 should be closed, pipes k k connected with cocks 4 and 5, and for the purpose of lessening carbonization when necessary by closing other cocks. Cock No. 10 in carbonizer C is to draw off surplus liquids that may be inadvertently poured in.

Letter D represents a globular or egg-shaped vessel with one partition, extending from the top to within about two inches of the bottom, with one dip-pipe in each compartment, which are connected by the half-circular pipe through and over the top with an outlet in each section. In the center of the bottom is a cock, No. 11, for drawing off the contents. The inlets I I, with screw-caps, are for the purpose of filling the vessel or stirring its contents. Said vessel D should be filled only sufficient to cover the dip-pipes a a two and a half inches from their bottoms or lower ends. Said vessel D is used as a purifier. The articles used for purifying are high-proof alcohol or other suitable liquid and chloride of lime or chlorine-gas mixed in suitable proportions to answer the purpose.

Process of manufacturing chlorinated illuminating-gas by apparatus, represented by Figs. 1, 2, 3: Fill the holder with common air through

cock No. 1. Then close cock No. 1 and open cocks 2 and 3, by which the air will pass through pipe *c* and cock 3 into carbonizer C, then through pipes *b a* into compartments F F F, thence into and through outlet-pipe *e* into purifier D, and out of D through pipe *f* to the burner by opening cock No. 8.

We do not claim as our invention the manufacture of illuminating gas by forcing air over benzole, naphtha, or other liquids, simply, as that is already known.

We do claim—

Forcing the gas thus made through a mixture of alcohol and chloride of lime, thereby effecting such a change in said gas that it is not liable to refrigeration or condensation, and, also, so decarbonizing said gas to prevent smoke while burning, and prepare it for any kind of burner.

WARREN A. SIMONDS.
SETH WARNER.
